STOKER

Gordon A. Stephens, Long Branch, Ontario, Canada, assignor to American Engineering Company, Philadelphia, Pa., a corporation of Pennsylvania

Application July 2, 1936, Serial No. 88,545

10 Claims. (Cl. 122—4)

This invention relates to stokers, and more particularly to fluid cooled stokers of the multiple retort underfeed type.

One object of the present invention is to provide a simplified and generally improved stoker of the stated character.

Another object is to provide an improved fluid cooling system for stokers which insures proper circulation of the fluid therethrough under all conditions of operation with the use of a minimum of fluid connections with the source of fluid supply.

A further object is to provide a simplified and compactly arranged furnace comprising a continuous discharge stoker arranged adjacent the boiler and including a novel fluid system disposed in cooling relation with the stoker and the walls of the furnace.

Other and further objects of the invention will become apparent as the description of the invention progresses.

Of the drawings:

Fig. 1 is a longitudinal sectional view taken through one of the stoker retorts showing the arrangement of the boiler and the stoker of the furnace, and the improved fluid cooling system associated therewith.

Fig. 2 is a plan view partly in section taken substantially along line 2—2 of Fig. 1, and

Fig. 3 is a plan view of the fluid cooling system for the stoker.

Referring to the drawings, the numeral 1 designates generally a furnace comprising a boiler 2 fired by a multiple retort underfeed stoker 3. The boiler 2 in the present instance is of the vertical tube type and consists of a steam drum 4, a mud drum 5, and a series of substantially vertical banks of tubes 6 extending between said drums. The combustion chamber 7 of the furnace is bounded at the sides thereof by walls 8 and 9, at the front by a wall 10, at the top by an upwardly and rearwardly inclined wall 11, and at the rear by the forwardly disposed bank of boiler tubes 12. The walls 8, 9, 10 and 11 may be constructed of any suitable refractory material.

The side walls 8 and 9 have each provided therein adjacent stoker 3, a series of inclined tubes 13 and 14 respectively. Tubes 13 and 14 are connected at the upper ends thereof to headers 15 and 16 respectively, disposed outwardly of front wall 10, and at their lower ends to mud drum 5. Tubes 13 and 14, and the lower portions of tubes 12 may be covered by protective

blocks 17 to protect them against the action of the fuel and ash, if it is so desired.

The stoker 3 in the present instance comprises an underfeed section 18 consisting of alternately disposed retorts 19 and tuyère rows 20, and an overfeed extension grate section 21. Fuel is supplied to the stoker from hoppers 22 mounted exteriorly of the front wall which empty into cylinders 23 in line with the retorts, and rams (not shown) operating in said cylinders feed predetermined quantities of fuel to said retorts upon each reciprocation thereof. Fuel is underfed along the retorts 19 by a series of pushers 24. The rams and pushers are operated by any suitable power mechanism 25, the pushers being connected thereto by a link and lever mechanism indicated at 26. The lower end of each retort has provided therein a horizontally disposed dead plate 27, which lies in substantially the same plane as the overfeed section 21.

Extending rearwardly from a header 28 disposed transversely beneath the stoker are a series of fluid conducting tubes 29. These tubes are mounted in intimate relation with dead plates 27 and terminate in a second transversely disposed header 30. As shown more particularly in Figs. 2 and 3, each dead plate 27 has two tubes associated therewith, although it is apparent that the number of tubes so disposed may be varied without departure from the invention. Disposed between each pair of tubes 29 and extending forwardly from header 30 is a second pair of tubes 31. These tubes extend in parallel relation with tubes 29 between header 30 and the lower end of tuyère rows 20. Tubes 31 then incline upwardly and forwardly and make intimate contact with said tuyères, and then are bent upwardly so as to lie in abutting relation with walls 10 and 11 and terminate at their upper ends in the steam drum 4 of the boiler. Thus, tubes 31 not only cool a portion of the overfeed section 21 and the tuyères 20, but also cool the front and top walls of the combustion chamber 7. As shown in Figs. 1 and 2, headers 28 and 30 are supported on I beams 32 and 33 respectively, extending transversely of the stoker 3 and supported at the ends thereof in side walls 8 and 9. Header 28 is connected to drum 5 of the boiler by a pair of downtake connections 34 and 35, while headers 15 and 16 are connected to steam drum 4 by risers 36 and 37, respectively. As shown in Figs. 1 and 2, risers 36 and 37 extend through front wall 10 and lie in abutting relation with top wall 1 and thus also serve to cool a portion of said wall. It therefore is seen that fluid

from boiler 2 flows into header 28 through down-take connections 34 and 35, thence through tubes 29 to header 30, and thence through tubes 31 to steam drum 4, as indicated by the arrows in Fig. 3. By this construction it is unnecessary to provide additional connections between header 30 and the boiler 2.

Mounted on a rod 38, supported in bearings 38', attached at intervals to header 30, are a series of dump plates 39. A lever 40 secured to one end of rod 38 and disposed exteriorly of wall 8 is provided to adjust plates 39 to vary the size of the discharge opening 41 defined by said plates, the bank of tubes 12, and the rear wall 15 42 of an ash pocket 43, as shown in Fig. 1.

Draft air is supplied to the stoker by any suitable fan mechanism (not shown) and enters a plenum chamber 44 disposed beneath the stoker through a duct 45. This air passes between the 20 grates of the stoker and flows through the combustion chamber 7 and the various boiler passes, as indicated by the arrows in Fig. 1, and discharges to the stack through an opening 46 provided in the rear wall 41 of the furnace.

25 The overfeed grate section 21 in the present instance consists of a series of metallic or refractory blocks 48 secured to the rearwardly disposed portions of tubes 29 and 31, and the top surface of header 30. A slight space is provided between 30 the adjacent edges of these blocks through which draft air may pass to the fuel bed, overlying the same. Other forms of grate blocks may also be employed if it is so desired without departing from the invention. Draft air is supplied to extension grate 21 from plenum chamber 44 through the connecting passage 49. Dampers 50 may be provided in this passage to control the flow of air to the overfeed extension section 21, if it is so desired. Any siftings passing between blocks 35 48 of the extension grate section gravitate into a hopper 51 disposed therebeneath. These siftings may be removed from the hopper from time to time by simply opening a closure 52 provided at the bottom thereof.

45 From the foregoing description it is seen that a simplified and highly improved stoker has been provided. The grates, the dead plates and the overfeed grate section of the stoker, as well as the walls of the furnace, are effectively cooled by a simplified, as well as highly efficient cooling 50 system. Also, by arranging the boiler and stoker in the manner shown herein intermediate walls may be dispensed with. The arrangement of the dump plates in respect to the forwardly disposed 55 bank of boiler tubes further provides a continuous ash discharge construction wherein the rate of ash discharge may be varied to best suit the operating conditions of the furnace.

While the embodiment herein shown and described is admirably adapted to fulfill the objects primarily stated, it is to be understood that the invention is not to be limited thereto, since it may be embodied in other forms, all coming within the scope of the claims which follow.

60 65 What is claimed is:

1. In a furnace, the combination of a stoker, comprising alternately disposed retorts and tuyère rows, substantially horizontally disposed fuel supporting means provided at the lower end of each of said retorts, means comprising one or more fluid conducting tubes disposed longitudinally of and in cooling relation with said fuel supporting means, headers connecting the opposite ends of said tubes, a boiler, means connecting one of said headers with said boiler, means

comprising one or more tubes extending from the other of said headers and disposed in cooling relation with said tuyère rows, said last mentioned tubes being connected to said boiler whereby fluid from said boiler circulates to said first mentioned header and through said first mentioned tubes to said second header, thence through said second mentioned tubes and back to the boiler.

2. In a furnace, the combination of a stoker, comprising alternately disposed retorts and tuyère rows, a dead plate disposed at the lower end of each of said retorts and extending between adjacent tuyère rows, one or more fluid conducting tubes disposed longitudinally of and in cooling relation with each of said dead plates, front and rear headers connected to said tubes, a boiler, means connecting said front header to said boiler, one or more fluid conducting tubes extending from said rear header and disposed in cooling relation with each of said tuyère rows, a combustion chamber disposed above said stoker having front, side and top walls, said last mentioned tubes extending upwardly and lying in substantially abutting relation with said front and top walls and terminating in said boiler.

3. In a furnace, the combination of a stoker, comprising alternately disposed retorts and tuyère rows, a dead plate disposed at the lower end of each of said retorts, one or more fluid conducting tubes mounted in cooling relation with each of said dead plates, front and rear headers connected to said tubes, a boiler, means connecting said front header to said boiler, one or more fluid conducting tubes extending from said rear header and disposed in cooling relation with each of said tuyère rows, a combustion chamber disposed above said stoker having front, side and top walls, said last mentioned tubes extending upwardly and lying in substantially abutting relation with said front and top walls and terminating in said boiler, means comprising a series of fluid conducting tubes disposed adjacent each of said side walls, a header connected to one end of each of said series of tubes, the other end of said tubes being connected to said boiler, and risers connecting said headers with said boiler, said risers lying in substantially abutting relation with said top wall.

4. In a furnace, the combination of a stoker having an underfeed section and an overfeed section, said underfeed section consisting of alternately disposed retorts and tuyère rows, fuel supporting means disposed at the lower ends of said retorts and extending between adjacent tuyère rows, said fuel supporting means being disposed in substantial alignment with said overfeed section, fluid conducting means mounted in cooling relation with said fuel supporting means, overfeed section, and tuyère rows, and means for supplying fluid to said fluid conducting means.

5. In a furnace, the combination of a stoker having an underfeed section and an overfeed section, said underfeed section consisting of alternately disposed retorts and tuyère rows, dead plates disposed at the lower ends of said retorts and in substantial alignment with said overfeed section, fluid conducting means mounted in cooling relation with said dead plates, overfeed section, and tuyère rows, and means for supplying fluid to said fluid conducting means.

6. In a furnace, the combination of a stoker having an underfeed section and an overfeed section, said underfeed section consisting of alternately disposed retorts and tuyère rows, fuel supporting means disposed at the lower ends of said

- retorts and extending between adjacent tuyère rows, said fuel supporting means being disposed in substantial alignment with said overfeed section, one or more fluid conducting tubes mounted in 5 cooling relation with said fuel supporting means and portions of said overfeed section, front and rear headers connected to the opposite ends of said tubes, one or more fluid conducting tubes extending forwardly of said rear header and in cool- 10 ing relation with other portions of said overfeed section, and means for supplying fluid to said front header.
7. In a furnace, the combination of a stoker having an underfeed section and an overfeed sec- 15 tion, said underfeed section consisting of alternately disposed retorts and tuyère rows, fuel sup- porting means disposed at the lower ends of said retorts and extending between adjacent tuyère rows, said fuel supporting means being disposed 20 in substantial alignment with said overfeed sec- tion, one or more fluid conducting tubes mounted in cooling relation with said fuel supporting means and portions of said overfeed section, front and rear headers connected to the opposite ends 25 of said tubes, one or more fluid conducting tubes extending forwardly of said rear header, a por- tion of each of said last mentioned tubes lying in substantially the same plane as said first men- 30 tioned tubes and in cooling relation with other portions of said overfeed section, and a portion of said last mentioned tubes lying in cooling relation with said tuyère rows, and means for circulating a cooling medium through said tubes and headers.
8. In a furnace, the combination of a stoker having an underfeed section, and an extension 35 grate section, said underfeed section consisting of alternately disposed retorts and tuyère rows, fuel supporting means disposed at the lower end 40 of each of said retorts and extending between adjacent tuyère rows, said fuel supporting means being disposed in substantial alignment with said extension grate section, fluid conducting means mounted in cooling relation with said fuel sup- 45 porting means, extension grate section, and tuyère
- rows, and means for supplying fluid to said fluid conducting means.
9. In a furnace, the combination of a stoker having an underfeed section, and an extension grate section, said underfeed section consisting 5 of alternately disposed retorts and tuyère rows, fuel supporting means disposed at the lower ends of said retorts and extending between adjacent tuyère rows, said fuel supporting means being disposed in substantial alignment with said extension 10 grate section, one or more fluid conducting tubes mounted in cooling relation with said fuel supporting means and portions of said extension grate section, front and rear headers connected to the opposite ends of said tubes, one or more fluid 15 conducting tubes extending forwardly of said rear header, a portion of each of said last mentioned tubes lying in substantially the same plane as said first mentioned tubes and in cooling relation with other portions of said extension grate section, and 20 a portion of said last mentioned tubes lying in cooling relation with said tuyère rows, and means for circulating a cooling medium through said tubes and headers.
10. In a furnace, the combination with a boiler 25 having a plurality of banks of substantially vertical tubes, of a stoker comprising an underfeed section and an overfeed section for firing said boiler, said underfeed section consisting of alter- 30 nately disposed retorts and tuyère rows, a dead plate disposed at the lower end of each of said retorts and lying in substantially the same plane as said overfeed section, means for feeding fuel to and along said stoker, means comprising a series of fluid conducting tubes mounted in cool- 35 ing relation with said dead plates, overfeed sec- tion, and tuyère rows, means connecting said tubes to said boiler, adjustable dump plates disposed at one end of said stoker for supporting the residue fed from the latter, said dump plates being 40 spaced from one of the banks of tubes of said boiler forming a discharge opening for said residue, and means for adjusting said plates to vary the size of said discharge opening.

GORDON A. STEPHENS. 45
